UNITED STATES PATENT OFFICE

116,608

DESIGN FOR A COMBINED AUTOMOBILE HOOD AND AIR INTAKE GRILLES

Peter J. Miller and Richard C. Spooner, Detroit,
Mich., assignors to Evans Products Company,
Detroit, Mich., a corporation of Delaware

Application August 17, 1938, Serial No. 79,398

Term of patent 7 years

To all whom it may concern:

Be it known that we, Peter J. Miller and Richard C. Spooner, citizens of the United States, residing at Detroit, in the county of Wayne and State of Michigan, have invented a new, original, and ornamental Design for a Combined Automobile Hood and Air Intake Grilles of which the following is a specification, reference being had to the accompanying drawing, forming a part of this specification, wherein:

Fig. 1 is a perspective view of an automobile hood showing our new design,

Fig. 2 is an enlarged perspective view of a portion of the structure illustrated in Fig. 1 showing in greater detail one of the grilles shown in solid lines in Figure 1.

Fig. 3 is a plan view of the grilles shown in Fig. 2, and

Fig. 4 is a section taken on the line 4—4 of Fig. 3.

The dominant features of our design reside in the air intake grille elements shown in solid black lines in the drawing.

We claim:

The ornamental design for a combined automobile hood and air intake grilles, substantially as shown and described.

PETER J. MILLER.
RICHARD C. SPOONER.
